UNITED STATES PATENT OFFICE.

ETHAN I. DODDS, OF PULLMAN, ILLINOIS, ASSIGNOR TO THE PULLMAN COMPANY, OF CHICAGO, ILLINOIS, A CORPORATION OF ILLINOIS.

RAILWAY-CAR TRUCK.

No. 825,035.

Specification of Letters Patent.

Patented July 3, 1906.

Application filed September 7, 1905, Serial No. 277,434.

To all whom it may concern:

Be it known that I, ETHAN I. DODDS, a citizen of the United States, residing at Pullman, in the county of Cook and State of Illinois, 5 have invented certain new and useful Improvements in Railway-Car Trucks, of which the following is a specification.

Since cast-metal columns for car-trucks have the disadvantage that they more or 10 less readily break at the top and bottom, I have invented an improved truck including columns of pressed or rolled metal, preferably steel or wrought-iron, to replace the cast ones, and coöperating with these pressed or 15 rolled columns I use base-blocks and caps recessed to receive the bottom or inverted and top arch-bars, respectively. In my novel truck I also employ an improved type of spring-plank, which is depressed at its cen- 20 tral portion, thus permitting the use of a wide and deep bellied truck-bolster, the spring- plank being preferably made up of end and central rolled or pressed sections riveted together, the central section acting as a spacer 25 for the inverted arch-bar and bottom tie-bar. The rivets which unite the sections of the spring-plank also pass through and hold in place the brake-hangers.

In the accompanying drawings I have illus- 30 trated a practical form of my invention, like reference characters on all the figures referring to the same parts.

Figure 1 is a plan view of a car-truck embodying my invention. Fig. 2 is a side view 35 of the truck shown in Fig. 1, the wheels being indicated by dotted lines and the journal-boxes being entirely omitted. Fig. 3 is a partial elevation and a partial section illustrating the adaptability of the truck to a 40 deep-bellied truck-bolster and showing also the body-bolster. Fig. 4 is a perspective view of the cap used at the top end of the column. Fig. 5 is a perspective view of a portion 45 of the parts constituting the side frame and spring-plank of the truck. Fig. 6 shows in perspective the base-block used at the bottom of the column; and Fig. 7 is a cross-section of the spring-plank, showing the brake-hanger in elevation.

50 Referring first to Fig. 3, 10 represents any usual type of body-bolster, the same being supplied on its lower edge with a center-bearing plate 11 and side bearings 12. Beneath this body-bolster is a bellied truck-

bolster 13, which has on its upper surface 55 center-bearing plate 14, coöperating with plate 11 of bolster 10, and side bearings 15, acting in conjunction with side bearings 12 of the body-bolster. The side frame of the car-truck comprises the top arch-bar 16, the in- 60 verted or bottom arch-bar 17, and the bottom tie-bar 18, the ends of truck-bolster 13 extending between and beyond the columns of the side frames. The two side frames of the truck are spaced apart and tied together 65 by a novel form of spring-plank, which has end channel portions 19, with their flanges extended upwardly, and a central channel-section 20, which has its flanges extended downwardly, the central channel being riveted to 70 the inner ends of the end channel-sections, the rivets also passing through and holding in place brake-hangers 21, which rest in the troughs of channels 19. This construction, which includes a depressed or lowered 75 central part of the spring-plank, allows the use of a deeper and wider truck-bolster than has been usual without sacrificing the strength and bending resistance of the spring-plank.

Central channel-section 20 is of such a 80 length that its ends abut against and space apart the bottom tie-bars 18 and the inverted arch-bars 17. Wooden spring-blocks 22 rest in the end channel-sections 19, the lower ends of springs 23 pressing against the wooden 85 blocks, the upper ends of the springs sustaining the truck-bolster 13, which is supplied on its sides with guides 24, adapted to coöperate and slide upon the columns to be described. 90

Instead of the usual cast-metal columns I employ columns made of two pressed or rolled members, the inner plate member 25 of each column, which has parallel longitudinal edges for the greater portion of its 95 length, being provided at its lower end with edgewise-projecting ears 26, which permit the passage of bolts 27 through perforations therein, the bolts also extending through the upwardly-projecting flanges of the end 100 spring-plank section 19. To each plate 25 is riveted, as is most clearly shown in Fig. 5, a pressed or rolled member 28, having an integral hollow rib 29 and outwardly-extended flanges, the uniting-rivets passing through 105 these flanges. These two members riveted together constitute a column which replaces the usual cast-metal column. At the top

end of each column there is provided a cap 30 of the type shown in Fig. 4, which has a stem 31, adapted to fit within the hollow rib 29 of the column, the upper surface of the cap being countersunk at 32 to receive the top arch-bar, a perforation 33 passing through the entire cap, for a purpose to be explained below. At the lower end of each column there is supplied a base-block 34 of the shape illustrated in Fig. 6, the block having perforated ears 35, through which bolts 27 pass to hold the same in place against the column. The upper surface of block 34 has a recess 36, adapted to fit about the lower end of rib 29, and also has a projection 37, adapted to fit in the lower end of the hollow rib. To keep the inverted arch-bar 17 in place, the bottom and end inclined surfaces of base-block 34 are countersunk at 38, the block also being provided with a perforation 39, passing completely through the block, including projection 37.

When all the parts are in place, column-bolts 40 pass through holes in the top arch-bar, perforations 33 of the caps, hollow ribs 29, apertures 39 of the base-blocks, and holes in the inverted arch-bar 17 and bottom tie-bar 18, nuts 41 at the lower ends of the bolts holding all the parts securely in place. Bolts 27 hold the columns and base-blocks in position, so that the latter, by means of their recesses within which the inverted arch-bars rest, keep in place these latter members, the caps 30, together with bolts 40, positioning the top arch-bars.

Minor mechanical changes may be made in this structure without departing from the substance of my invention as set forth in the appended claims.

40. This patent is intended to embrace only so much of the disclosure made herein as is covered by the claims.

I claim—

45. A car-truck having a spring-plank with standard beam ends and a similar inverted beam for its central portion, substantially as described.

50. A car-truck having a spring-plank with standard beam ends and a similar inverted beam for its central portion, and brake-hangers riveted to said end and central portions, substantially as described.

55. A car-truck having a spring-plank with channel ends having flanges extended in one direction and a channel central portion with its flanges extended in the opposite direction, substantially as described.

60. A car-truck having a spring-plank with channel ends having their flanges extended in one direction, and a channel central portion with its flanges extended in the opposite direction, and a brake-hanger at each end riveted to the end and central portions, substantially as described.

5. A car-truck having a spring-plank with 65 channel ends having flanges extended upwardly and a channel central portion with its flanges extended downwardly, a brake-hanger at each end between the flanges of the end portions, and rivets uniting said brake-hangers and end and central portions, substantially as described.

6. A car-truck having in combination an arch-bar on each side, and a spring-plank comprising standard beam ends and a standard beam central portion secured to said beam ends, said central beam abutting against and spacing apart said arch-bars, substantially as described.

7. A car-truck having in combination an 80 arch-bar and a tie-bar on each side, and a spring-plank comprising channel end portions with their flanges extended upwardly, and a channel central portion riveted to said end portions and having its flanges extended 85 downwardly, the ends of said central portion abutting against and spacing apart said arch-bars and tie-bars, substantially as described.

8. In a car-truck, a column having two upright metal members riveted together, one 90 of said members having a hollow rib for the passage of a column-bolt, substantially as described.

9. In a car-truck the combination of a flanged spring-plank, a column-plate secured 95 to a flange of said plank, and a ribbed member riveted to said column-plate, substantially as described.

10. In a car-truck, the combination of a flanged spring-plank, a column-plate secured 100 to a flange of said spring-plank, and a second plate with a hollow rib riveted to said column-plate, substantially as described.

11. In a car-truck, the combination of a column having a rib, and a base-block 105 provided with means to fit said rib and having a recess to receive the bottom or inverted arch-bar, substantially as described.

12. In a car-truck, the combination of a column having a rib, and a base-block 110 provided with a recess to fit said rib externally and a recess to fit the bottom or inverted arch-bar, substantially as described.

13. In a car-truck, the combination of a column having a hollow rib and a base-block 115 supplied with a recess to fit said rib, a projection to extend within said rib, and a recess to fit the bottom or inverted arch-bar, substantially as described.

14. In a car-truck, the combination of a column comprising two plates riveted together, one of said plates having a hollow rib, and a base-block having a recess to fit the outer surface of said rib, a projection to extend inside of said rib, and a recess to fit 125 the bottom or inverted arch-bar, substantially as described.

15. In a car-truck, the combination of a

column having a rib, a top cap to fit said rib, said cap being countersunk on top to receive the top arch-bar, substantially as described.

16. In a car-truck, the combination of a column having a hollow rib, a top cap with a stem fitting in said rib, said cap being countersunk on top to receive the top arch-bar, substantially as described.

17. In a car-truck, the combination of a

column comprising two plates riveted together, one of said plates having a hollow rib, a top cap having a stem to fit in said rib, said cap being countersunk on top to receive the top arch-bar, substantially as described.

ETHAN I. DODDS.
